UNITED STATES PATENT OFFICE.

WILLIAM I. COOLEY, OF SALTVILLE, VIRGINIA, ASSIGNOR TO WILLIAM R. DAWSON, OF ROANOKE, VIRGINIA.

HOLLOW-PISTON WATER-VALVE.

1,275,854.

Specification of Letters Patent. Patented Aug. 13, 1918.

Application filed March 1, 1917. Serial No. 151,841.

To all whom it may concern:

Be it known that I, WILLIAM I. COOLEY, a citizen of the United States, residing at Saltville, in the county of Smyth and State of Virginia, have made a certain new and useful Invention in Hollow-Piston Water-Valves, of which the following is a specification.

Figure 1 is a central longitudinal section 10 of the valve casing and valve, the tubular valve member being moved downward to engage the other valve member.

Fig. 2 is a section on the line 3—3, Fig. 1.

Fig. 3 is a fragmentary sectional view 15 showing the tubular valve member raised from the other valve member.

Fig. 4 is a detail side view, partly in section, of the hollow valve member, the stand pipe and the valve casing, parts being broken 20 away.

The invention has relation to valves including a reciprocating hollow sleeve or piston member, for use mainly in supplying water to locomotive engines and fire hydrants, and it consists in the novel construction and combinations of parts as herein-after set forth.

In the accompanying drawings illustrating the invention, 4 designates the valve casing, 30 having at one side an inlet 5 from the water main, said casing forming a support for the stand-pipe 2, the latter at its lower end revolvably mounted upon the valve casing at 2^a.

Mounted within the casing 4 is a support 35 7, for a yieldable valve member 8, said support being usually in the form of a plug, fitting in an opening 9 in the bottom of the casing and suitably secured therein.

The valve member 8 is preferably formed 40 of soft rubber and is provided with a cylindrical base 10, fitting in a cylindrical seat 11 of the plug or support, and with an upwardly extending frusto-conical portion 12, having a flat top 13, and side walls of an 45 inclination approaching the vertical. This member 8 is centrally perforated at 14, a leather washer 15 overlying the same and being also of frusto-conical form, a metal washer 16 overlying the leather washer and 50 being also of frusto-conical form but of lesser diameter than the leather washer, a securing screw 17 engaging central perforations of the two washers, and the central perforations of the valve member 8 and of its 55 support 7, the latter having an internal screw

thread. This screw has a rounded head 18, the side walls of which merge into the conical side walls of the washer 16.

19 designates the hollow cylindrical or tubular valve member, having sliding movement upwardly and downwardly within an opening 20, of the top of the valve casing, provided with a stuffing box 21, the lower end of said tubular member being of an internal diameter slightly less than the external diameter of the bottom of the frusto-conical portion of the valve member 8, so that in the downward movement of the tubular member, the side walls of the frusto-conical member will be engaged thereby to 70 close the valve and stop the flow of water previous to or coincident with the engagement of the bottom of the tubular member with the top of the base of the other member. In this way a wedging engagement of the 75 tubular member with the yieldable valve member is accomplished over a comparatively large area of surface, whereby the valve is more effectually closed and cutting of the yieldable valve member is avoided. 80

The frusto-conical valve member being compressed by the engagement therewith of the tubular member is rendered substantially cylindrical and is allowed to expand slightly in an upward direction owing to 85 the yieldable leather washer 15 overlying the same.

The tapered valve member 8, together with the tapered head of the securing screw and the frusto-conical or tapered washers 90 facilitate the passage of the water into the stand pipe when the valve is open.

The tubular valve member 19 at its upper portion fits closely at 22 within the lower end of the stand pipe 2, having sliding movement 95 therein, and is provided at its upper end with a cross-arm 23, the lower end of the operating rod 24 for the valve having connection with said cross-arm.

It is designed to use a suitable relief valve 100 or valves in connection with this device in order to eliminate water hammer or vibration or to relieve undue pressure by the sudden closing of the valve. Such relief valves would ordinarily be added to the valve casing, and for extraordinary pressure it may be desirable to place a relief valve in the inlet pipe. 105

I claim:

In a valve, a stationary base, a perforated 110

frusto-conical resilient member resting upon said base, a perforated frusto-conical washer, a bolt extending through the perforations of said resilient member and said washer and 5 securing the same to said base, said bolt having an upper tapered head, and a hollow reciprocatory cylindrical member of rigid material having an internal diameter less than the diameter of the lower end portion 10 of said resilient member and greater than that of the upper portion thereof, the resilient member adapted to assume cylindrical form under engagement with the reciprocatory member to plug the end of the latter

over an extended area of surface, the side 15 walls of said washer merging into the side walls of the resilient member and the side walls of said head merging into those of said washer to facilitate the passage of fluid into the reciprocatory member when the 20 valve is open.

In testimony whereof I affix my signature in presence of two witnesses.

WILLIAM I. COOLEY.
